2,512,921

ROTARY CUTTER FOR SEVERING ROOTS
FROM VEGETABLESRalph K. Daugherty, San Jose, Calif., assignor
to Roy M. Magnuson

Application June 11, 1946, Serial No. 675,958

9 Claims. (Cl. 146—81)

1

The present invention relates to rooters for vegetables such as onions and beets and is concerned more particularly with a provision of a simplified power-driven rooter of this character constructed for manual positioning of the vegetable with respect to the rooting knife.

It is the general object of the invention to provide an improved rooter for vegetables such as onions and beets.

Another object of the invention is to provide a rooter of the above type which enables quick manual application of the vegetable to the rooting knife without danger of cutting the hand of the operator.

A further object of the invention is to provide a rooter of the above type which is fluid driven and is self-cleaning by virtue of the drive fluid.

Another object of the invention is to provide a rooter which is not apt to become clogged by the detached roots of the vegetables.

Further objects will be apparent from the following description of a preferred embodiment of the invention taken in connection with the accompanying drawings, in which:

Figure 1 is a transverse sectional view of the rooter as installed for operation.

Figure 2 is an elevational view of the rooter with the diaphragm cover removed.

The rooter of the instant invention comprises a hollow body or casing 10 of cast construction, having an upper opening surrounded by a cylindrical wall 11 and a lower discharge portion 12, of substantially rectangular contour which is offset with respect to the wall 11. Integral flanges 13 at either side of the discharge portion 12 provide for mounting of the rooter in operating position, for example, on a suitable support 14 for a vegetable conveyor or belt 15.

Within the casing 10 a rooting knife 16 is mounted coaxially with a central opening 17 in a diaphragm cover 18 of rubber or other suitable resilient material which is moulded upon a mounting sleeve 19. The central aperture 17 of the diaphragm is surrounded by a raised portion or rib 21 providing a limit stop for the fingers of an operator in applying an onion or other vegetable to the rooter. The cover 18 is shown in Figure 1 as having a peripheral portion parallel to the axis of the aperture 17 and extending a substantial distance towards the bottom of the rigid casing 10. As also shown in Figure 1, the cover 18 has intimate contact with the casing wall 11 so as to provide a fluid-tight seal.

The knife 16 is shaped to cut a conically-shaped section from the root of the vegetable and

2

is secured by a screw 22 centrally of a bearing retainer 23. The knife 16 which is mounted in fixed position on the impeller is provided with an outwardly projecting cutting tip in axial alignment with the impeller which is the first cutting portion of the knife presented to an article being processed and a cutting edge portion extending radially outwardly therefrom and then radially inwardly and downwardly to its point of mounting. The bearing retainer 23 is secured to an impeller 24 by suitable fastening screws 26. The impeller 24 is journaled by means of a ball bearing 27 upon an upper reduced portion 28 of an adjustable mounting post or stud 29 which is threaded within a boss 31 of the casing 10. The adjusted position of the post 29 and correspondingly of the impeller 24 and the knife 16 is maintained by a lock nut 32. The post 29 is apertured and receives a grease fitting 33 by means of which the interior cavity within the impeller 24 about the bearing 27 may be maintained filled with grease. The lower end of this cavity is provided with only a restricted communication with the interior of the casing by means of the inwardly projecting annular flange 34 of the impeller 24 and its close spacing to the bottom wall of the casing.

The impeller 24 is provided with a series of concave-faced impeller blades 24a of conventional form which are adapted to receive a jet of water from a jet fitting 36 suitably mounted within an inclined boss 37 of the bottom wall of the casing 10 immediately adjacent one side of the discharge portion 12 of the casing. A pipe 38 connects the jet fitting 36 to a suitable source of fluid under pressure such as a water pump for example.

In operation, the operator picks up a vegetable such as an onion from the conveyor 15 with the stem end of the vegetable in the palm of the hand and with the root end of the vegetable projecting out from the fingers. The vegetable is then placed with the root end engaging the aperture 17 and pressure is applied to depress the resilient diaphragm an appropriate amount in accordance with the size of the vegetable so that the root will engage the rapidly revolving knife 16 and will be cut from the vegetable.

The use of a liquid medium such as water for driving the impeller, the location of the jet with respect to the discharge opening and the impeller, and the dimensioning and mounting of the impeller within the casing and with respect to the discharge opening, all contribute to the effective discharge of cut portions of the vegetable 55 without clogging the equipment. Also the water

will maintain the knife clean so that a good cutting action is always present.

The diaphragm construction and its location with respect to the knife enables skilled operation in rooting without injury to the operator as the operator soon gets the "feel" of the rooter and can readily determine the necessary depth of cut in accordance with the size of vegetable. At the same time the annular rib 21 of the diaphragm provides a guard or a limit stop so that the operator feels free to press the vegetable into the rooter as long as the fingers are outside of this guard without danger of being cut.

While I have shown a preferred embodiment of the invention it will be understood that the invention is capable of variation and modification from the form shown so that its scope should be limited only by the scope of the claims appended hereto.

I claim:

1. In a vegetable rooter, a hollow casing for mounting in an inclined position and having a downwardly projecting discharge portion, an impeller journaled within said casing and substantially filling the lower portion thereof, an apertured diaphragm of flexible material on said casing, a knife mounted in fixed position on said impeller and having a cutting tip in axial alignment therewith, and a jet-fitting in said casing immediately adjacent said discharge portion and positioned to direct a fluid against said impeller from below the impeller.

2. In a vegetable rooter, a substantially cylindrical casing for mounting in an inclined position and having a downwardly projecting discharge portion having one side wall extending tangentially from the cylindrical portion of said casing, an impeller journaled within said casing and substantially filling the lower portion thereof, an apertured diaphragm of flexible material on said casing, a knife mounted in fixed position on said impeller and having a cutting tip in axial alignment therewith, and a jet-fitting in said casing immediately adjacent the wall of said discharge portion opposite to said one side wall and positioned to direct a fluid against said impeller from below the impeller.

3. A rooting and coring device of the class described, comprising a substantially cylindrical casing for mounting in an inclined position and having a downwardly projecting discharge portion, an apertured diaphragm of resilient material at one end of said casing, an impeller journaled within said casing, a knife carried by the impeller in alignment with the aperture in the diaphragm, and a jet-fitting in inclined position in the bottom wall of said casing positioned to direct a fluid against and upwardly through said impeller.

4. A rooting and coring device of the class described, comprising a substantially cylindrical casing for mounting in an inclined position and having a downwardly projecting discharge portion with one side wall extending tangentially from the cylindrical portion of said casing, an apertured diaphragm of resilient material at one end of said casing, an impeller journaled within said casing, a knife carried by the impeller in alignment with the aperture in the diaphragm, and a jet-fitting in inclined position in the bottom wall of said casing positioned to direct a fluid against and upwardly through said impeller and around said casing to said tangential side wall.

5. A rooting and coring device of the class described, comprising a substantially cylindrical

casing for mounting in an inclined position and having a downwardly projecting discharge portion, an apertured diaphragm of resilient material closing one end of said casing, an impeller in alignment with the aperture in the diaphragm, a knife carried by said impeller in fixed position thereon with a cutting tip in alignment with the axis of said impeller and said aperture, journaling means for said impeller comprising a post mounted in said casing coaxially with the aperture in said diaphragm and projecting within the impeller to be housed thereby and a bearing between said post and said impeller, said impeller being spaced closely from said post and from the bottom wall of the casing, and a jet-fitting in said casing positioned to direct a fluid against said impeller.

6. A rooting and coring device of the class described, comprising a substantially cylindrical

casing for mounting in an inclined position and having a downwardly projecting discharge portion with one side wall extending tangentially from the cylindrical portion of said casing, an apertured diaphragm of resilient material closing one end of said casing, an impeller in alignment with the aperture in the diaphragm, a knife carried by said impeller in fixed position thereon with a cutting tip in alignment with the axis of said impeller and said aperture, journaling means for said impeller comprising a post

20 mounted in said casing coaxially with the aperture in said diaphragm and projecting within the impeller to be housed thereby and a bearing between said post and said impeller, said impeller being spaced closely from said post and from the bottom wall of the casing, and a jet-fitting in said casing positioned to direct a fluid against

25 said impeller.

7. A rooting and coring device of the class described, comprising a substantially cylindrical

casing for mounting in an inclined position and having a downwardly projecting discharge portion with one side wall extending tangentially from the cylindrical portion of said casing, an apertured diaphragm of resilient material closing one end of said casing, an impeller in alignment with the aperture in the diaphragm, a knife carried by said impeller in fixed position thereon with a cutting tip in alignment with the axis of said impeller and said aperture, journaling means for said impeller comprising a post

30 mounted in said casing coaxially with the aperture in said diaphragm and projecting within the impeller to be housed thereby and a bearing between said post and said impeller, said impeller being spaced closely from said post and from the bottom wall of the casing, and a jet-fitting in said casing positioned to direct a fluid against

35 said impeller and around said casing to said tangential side wall.

8. In a vegetable rooter, a hollow relatively rigid casing; a rooting knife mounted for rotation in said casing and having a cutting part disposed radially outward of the knife axis of rotation; and a diaphragm of resilient material extending across said casing and being in fluid-tight sealing relationship with said casing and constituting the sole support for the vegetable, and having an aperture axially aligned with the axis of rotation of said knife and sufficiently

40 large to allow the cutting part of the knife in its rotation to project therethrough, said diaphragm being flexible and deformable in cross section throughout a substantial annular area surrounding said aperture for enabling a vegetable positioned over said aperture and pressed against said

45 diaphragm to be moved into engagement with said knife.

9. In a vegetable rooter, a hollow casing including a rigid part; a rooting knife mounted for

50 rotation on said rigid part and in said casing and having a cutting part disposed radially outward of the knife axis of rotation; and a diaphragm of resilient material extending across the end of said casing and peripherally parallel

55 to the axis thereof a substantial distance, and being in fluid-tight sealing relationship with said casing part and constituting the sole support for the vegetable, and having an aperture axially aligned with the axis of rotation of said knife

60 and sufficiently large to allow the cutting part of the knife in its rotation to project therethrough, said diaphragm being flexible and deformable in cross section throughout a substantial annular area surrounding said aperture for enabling a

65 vegetable positioned over said aperture and

70 75

pressed against said diaphragm to be moved into engagement with said knife.

9. In a vegetable rooter, a hollow relatively rigid casing; a rooting knife mounted for rotation in said casing and having a cutting part disposed radially outward of the knife axis of rotation; a diaphragm of resilient material extending across said casing and being in fluid-tight sealing relationship with said casing and constituting the sole support for the vegetable, and having an aperture axially aligned with the axis of rotation of said knife and sufficiently large to allow the cutting part of the knife in its rotation to project therethrough, said diaphragm being flexible and deformable in cross section throughout a substantial annular area surrounding said aperture for enabling a vegetable positioned over said aperture and pressed against said diaphragm to be moved into engagement with said knife; and means for maintaining said knife against axial movement relatively to said casing, whereby

relative axial movement of said casing and a vegetable pressed against said diaphragm for engagement with said knife is effected solely by deforming of said diaphragm.
